UNITED STATES PATENT OFFICE.

HENRY E. LONGWELL, OF CHICAGO, ILLINOIS, ASSIGNOR TO WESTINGHOUSE, CHURCH, KERR & COMPANY, OF NEW YORK, N. Y.

STEAM-SEPARATOR.

SPECIFICATION forming part of Letters Patent No. 459,498, dated September 15, 1891.

Application filed July 7, 1890. Serial No. 357,949. (No model.)

To all whom it may concern:

Be it known that I, HENRY E. LONGWELL, of Chicago, in the county of Cook and State of Illinois, have invented certain new and useful Improvements in Steam-Separators; and I do hereby declare that the following is a full, clear, and exact description thereof, reference being had to the accompanying drawings, and to the letters of reference marked thereon, which form a part of this specification.

This invention has for its primary object to provide automatic means for preventing the passage of water from steam-separators into or through the pipe to which it is desired to furnish dry steam in case the separator becomes flooded from any cause.

The invention has for another object to provide the separator with an alarm device denoting the presence of an excessive accumulation of water therein or that the cessation of steam flow to the engine or other apparatus is due to such excess of water in the separator-chamber.

In the use of steam-separators the water-discharge pipe of the separator occasionally becomes stopped or otherwise fails to carry off the water accumulated in the separator-chamber, and such accumulated water is sometimes thrown forward through the steam-pipe to the engine or other apparatus supplied by such steam-pipe with more or less disastrous results.

By the first feature of the present invention it is proposed to obviate this difficulty automatically through the agency of a valve in the steam pipe or passage leading to or from the separator and closed by the action of the water accumulated thereby.

By the second feature of the invention it is proposed to sound an alarm denoting that the cessation of steam-flow to the engine or other apparatus, resulting from the closure of the valve referred to, is due to an excess of water in the separator, in order that the attention of the engineer may be at once directed to the place of the difficulty.

This invention is adapted to be applied to any form of separator and may be made a

part of the separator itself or applied as an attachment thereto.

In the accompanying drawings, illustrating certain forms of my invention, Figure 1 is a central vertical section of a steam-separator of familiar construction, having all features of my improvement applied thereto, the valve and its closing mechanism being shown as a part of the separator apparatus. In this figure the inlet and outlet steam passages of the separator are arranged on opposite sides of the separator-chamber at its top. Fig. 2 is a side elevation of the upper portion of the separator as constructed in Fig. 1, looking from right to left of the latter figure, a part of the flange being broken away. Fig. 3 is a side elevation of a separator having inlet and outlet at the top and bottom, respectively. In this figure the float belonging to the valve mechanism is arranged within the separator-chamber; but the valve itself is arranged in a detachable section of the outlet-pipe. Fig. 4 represents the same kind of a separator as that shown in Fig. 3, but illustrates the float-chamber as distinct from the separator-chamber and the valve in a detachable portion of the outlet-pipe. Fig. 5 is a side elevation of a separator having lateral inlet and outlet steam passages at the upper end of the separator-chamber and having a separate float-chamber and a detachable pipe-section containing the valve.

Describing the figures of the drawings in their order, A, Fig. 1, represents a steam-separator, of which a and a' are respectively the inlet and outlet steam pipes, arranged opposite each other at the top of the separator-chamber. A' is the pipe leading from the bottom of the separator-chamber, through which the water taken from the steam by the latter should be normally withdrawn either to a trap or some other device for its proper disposition.

In one of the passages a or a' , and preferably in the outlet-pipe a' , is arranged a butterfly-valve B , working on a shaft b , which passes through a stuffing-box b' , Fig. 2, in the side of the pipe a' . Exterior to the pipe a' the shaft b is provided with an arm b^2 , carry-

ing a weight b^3 , by which weight, when unopposed, the valve B will be turned into its position to close the passage a' . As a suitable means for locking the valve B in its open position, so long as the separator shall contain no undue accumulation of water, the valve B is provided with a quadrant-shaped web b^4 on its under side, presenting a shoulder at b^5 . With this shoulder engages a vertically-movable rod C, which at its lower end is attached to one extremity of a centrally-pivoted lever C', that carries at its opposite end a float C². The rise of the float C² by an undue accumulation of water in the lower part of the separator-chamber will vibrate the lever C' upon its pivot c, depress the rod C out of engagement with the shoulder b^5 , and release the valve B, so that it will automatically rotate into a position to close the pipe a' by action 20 of the weight b^3 .

In Fig. 3 a butterfly-valve corresponding with that shown in Fig. 1 is secured to the shaft b, which is pivoted in a detachable portion a^2 of the outlet-steam pipe of the separator A, and the external weight-arm b^2 is provided with a latch b^6 , the upper end of which projects laterally to form a shoulder at b^7 . The float seen at dotted lines at C² is attached to an arm C', that is rigidly secured 25 to a shaft c, which in this instance projects through the side of the separator and is externally provided with the weight-arm c', carrying a weight C³. Said shaft c is also provided with an arm c², having its lower end 30 bent laterally to catch beneath the shoulder b^7 of the latch b^6 on the weight-arm b^2 of the valve. The rise of the float C² from an undue accumulation of water in the separator-chamber will swing the arm c² laterally from beneath the shoulder b^7 and release the weight-arm of the valve, so that the weight may fall and turn the valve into its closed position within the pipe a^2 . The application of a weight-arm c' and weight C³ to the shaft c is 35 not essential, but enables a solid float C² to be employed instead of a hollow one. Such external weight-arm may obviously be applied to the shaft c in Fig. 1.

In Fig. 4, A² is a water-chamber in communication with the separator-chamber through the pipes A' and a³ at its lower end and through the pipe a⁴ at its upper end. The float is arranged within this auxiliary chamber A², instead of in the separator-chamber A, and, as illustrated, the shaft c of the float device has its rigid arm c² bent at its lower end to engage with the straight weight-arm b^2 of the valve, said valve being in this instance arranged within a detachable extension a^2 of 55 the outlet-pipe.

In Fig. 5 the separate float-chamber A² opens at its upper end directly into the detachable valve-chamber a² and communicates at its lower end through a pipe a³ with the 60 water-delivery pipe A' of the main separator-chamber. As shown in this figure, the float C²

connects with a pivoted float-arm C' by means of a vertical rod c³, and the rotatable shaft c has its rigid locking-arm c² arranged vertically to stand beneath the end of the weight-lever b^2 of the valve. The valve is in this instance located in a detachable section a^2 of the outlet-pipe, as in the preceding Figs. 3 and 4.

Recurring to Fig. 1, D represents a high-water alarm of familiar construction containing a float which is connected with a valve at the upper end of the steam and water chamber D', through which valve steam on the elevation of the float is admitted to a whistle 75 or other alarm device. The steam which sounds the alarm is admitted to the chamber D' through the pipe d', communicating with the steam-space of the separator-chamber at a point above that to which water may accumulate in the separator before the valve-actuating float C² shall release the valve B. This alarm device will be likely to act in case of failure on the part of the valve-closing mechanism and signal to the engineer the presence of an excessive quantity of water in the separator-chamber. It will also act in conjunction with the valve-controlling mechanism to signal the engineer that the stoppage 80 of the engine or other apparatus worked 90 through the separator is due to flooding of the separator, and he may therefore proceed at once to the source of the difficulty.

The variety of figures here illustrated is intended to indicate that the invention may be applied to various forms of separators and in numerous ways while preserving its characteristic mode of operation, and I do not wish to be limited to either or all of the particular constructions shown, inasmuch as various other modifications may be employed without departure from said invention.

I claim as my invention—

1. The combination, with a steam-separator having inlet and outlet steam passages, of a valve applied to one of said passages, a float subject to the action of water accumulated by the separator, and intermediate mechanism engaged with said valve and operated by the float to effect the closure of the valve.

2. The combination, with a steam-separator having inlet and outlet steam passages, of an automatically-closing valve applied to one of said passages, and a float mechanism subject to the action of water accumulated by the separator and having a catch connection with the valve which is released by the rise of the float.

3. The combination, with a steam-separator, of a separate float-chamber located outside of and communicating with the separating-chamber, a separate valve-chamber connected in a steam-passage of the separator, a valve in said valve-chamber, and a float in the float-chamber arranged to effect the closure of the valve upon the rise of the float.

4. The combination, with a steam-separa-
tor provided with a valve in one of its steam-
passages, and a float mechanism for closing
said valve by the water accumulated by the
5 separator, of a high-water alarm arranged to
signal an undue accumulation of water in the
separator.

In testimony that I claim the foregoing as
my invention I affix my signature in presence
of two witnesses.

HENRY E. LONGWELL.
